SPACEBAND TOOL

George L. Curle, Minneapolis, Minn.

Application May 3, 1948, Serial No. 24,809

1 Claim. (Cl. 294—103)

1

My present invention relates to a novel tool for placing space bands in the space band box of a "linotype" machine, or in removing the same therefrom.

It is well known that it is a difficult operation, for the average person, to place space bands in the space band box of a "linotype" machine or to remove the same therefrom, due to the narrow width of said box and its inconvenient position in the "linotype" machine. Furthermore, due to the longitudinal taper of space bands, a considerable amount of gripping pressure is required to hold a plurality thereof in assembled relation when placing the same in a space band box or when removing the same therefrom. If too much gripping pressure is applied, the intermediate space bands will be squeezed out and the entire lot spilled, or if too little pressure is applied, the same thing will happen.

The object of this invention is to provide a novel tool for holding a plurality of space bands in assembled relation with a clamping action while placing the same in a space band box or while removing the same therefrom.

To the above end, the invention consists of the novel construction and arrangement hereinafter described and defined in the claim.

In the accompanying drawing, which illustrates the invention, like characters indicate like parts throughout the several views.

Referring to the drawing:

Fig. 1 is a view partly in elevation and partly in central longitudinal section, of the transverse channel and the space band box of a "linotype" and also showing the improved tool holding a plurality of space bands in said box;

Fig. 2 is an elevational view of the improved tool;

Fig. 3 is a sectional view of the tool taken on the line 3—3' of Fig. 2 and an elevational view of a space band held by the tool; and

Figs. 4 and 5 are detail views in section taken on the lines 4—4 and 5—5 of Fig. 2, respectively.

For the purpose of showing the improved tool 6 as used in handling space bands, there is shown in Fig. 1 of the drawing, the transfer channel 7 and the space band box 8 of a "linotype" machine. A portion of the transfer channel 7 is broken away and the space band box is shown in central longitudinal section. Matrices are delivered into the transverse channel 7 from the first elevator, not shown. Space bands are placed in the space band box 8 and successively released therefrom by an escapement 9, partially shown, into a spout

2

16 during the operation of the machine. The spout 10 directs the space bands to the assembler, not shown.

Each space band 11 includes a shaft 12 having therein a longitudinal slot 13 and a sleeve 14 slidably thereon and having supporting ears 15. Space bands 11 in the space band box 8 are held suspended by their ears 15 from the forwardly and downwardly inclined upper edges 8^a of the side 8^b of said box for sliding movement toward the escapement 9, and with their lower ends spaced above the bottom 8^c of the space band box 8. The outermost space band 11, at its lower end portion, engages the inner member 10^a of the spout 10 as a stop. During the operation of the escapement 9, it lifts the outermost space band 11 out of engagement with the spout member 10^a and then releases the same into the spout 10 where it is conveyed to the assembler. The space bands 11 at their lower ends are relatively thick and tapered to feather ends at their upper ends.

The parts thus far described are all of standard and well known construction and have been illustrated simply to show the use of my improved space band tool.

Referring now in detail to the space band tool 6, the same includes a body member 16 which is formed of a single flat bar, one end portion of which affords a handle 17. The tool 6, when in an operative position, is held edgewise in a vertical plane and it may be assumed to be in this position when hereinafter referred to. The opposite end portion of the body member 16, from the handle 17, is curved downwardly, as indicated at 18, and the under edge thereof affords a cam 19, for a purpose which will presently appear. Integral with the curved section 18 of the body member 16 is a forwardly extended space band carrier 20, the under edge of which is a continuation of the cam 19. This carrier 20 is considerably narrower than the body member 16 and integral with the outer end thereof is an upstanding fixed jaw 21. On the inner end of the carrier 20, in opposing relation to the jaw 21, is a stop shoulder 22. The edge portion of the carrier 20 between the jaw 21 and the stop shoulder 22 is straight and parallel to the upper edge of the body member 16 except at its forward end portion which is forwardly and downwardly inclined to the jaw 21 as indicated at 20^a.

A movable jaw 23 is slidably mounted on the body member 16 for co-operation with the fixed jaw 21. The movable jaw 23 is a channel member through which the body member 16 extends.

The side members 24 of the movable jaw 23 are

of substantially the same width as the body member 16 and have therein opposing longitudinal slots 25.

The slots 25 are on the arcs of circles having a common center and radii of substantially the same length as a radius extending from the lower end of one of the space bands 11 in the space band box 8 to a center at the intersection of the extension of the outer faces of the two outermost space bands 11 in said box. This, of course, is only approximate as the number of space bands 11 in the space band box 8 vary from time to time. Secured in the body member 16 is a transverse pin 26, the end portions of which extend into the slots 25 and hold the body member 16 and the movable jaw 23 in assembled relation. These slots 25 and the pin 26 limit the sliding movement of the movable jaw 23 relative to the fixed jaw 21 and also permit tilting of the movable jaw 23 produced by the engagement of the bottom member of said jaw with the cam 19.

The right-hand side member 24 of the movable jaw 21, at its upper rear corner, is upwardly extended and laterally offset to afford a thumb-piece 28. A hand 20^a is shown in Fig. 1 holding the tool 6 with the thumb 20^b pressed against the thumb-piece 28 to hold the movable jaw in engagement with the innermost space band 11 and with the group of space bands 11 clamped between the two jaws 21 and 23. The purpose of the inclined surface 20^a at the fixed jaw 21 is to facilitate the transfer of the outermost space band 11 to the escapement 9.

To place a plurality of the space bands 11 in the space band box 8, the fixed jaw 21 and the carrier 20 are inserted through the aligned slots 13 in the space bands in a tray. Next, the operator places the thumb ^b of his hand against the thumb-piece 28 and slides the movable jaw 23 relative to the body member 16, into engagement with the innermost space band 11. During this movement of the movable jaw 23, the engagement thereof with the cam 19 tilts the same downwardly so that its outer end is in flat engagement with the adjacent space band 11 so that opposing pressure is applied by the jaws 21 and 23 to the space bands 11 therebetween. While the space bands 11 are still held by the jaws 21 and 23, the operator positions the tool 6 longitudinally over the open tops of the transverse channel 7 and the space band box 8 and lowers said tool to position the space bands 11 in the transfer channel 7 and the space band box 8, and thus moves the tool 6 endwise forwardly until stopped by the engagement of the fixed jaw 21 with the closed front end of the space band box 8 and with the shafts 12 resting on the bottom 8^c of said box. Finally, the operator releases the movable jaw 23 by removing his thumb from the thumb-piece 28 and lowers the outer

end portion of the tool 6 until the fixed jaw 21 is free to be withdrawn through the slots 13 by a rearward endwise movement of the tool 6.

To remove space bands 11 from the space band box 8, the operator inserts the tool 6 into the space band box 8 and projects the carrier 20 and fixed jaw 21 through the slots 13 and then lifts the outer end portion of the tool 6 to bring said jaw into engagement with the outermost space band 11. Next, the operator places his thumb against the thumb-piece 28 and presses the movable jaw 23 forwardly to clamp the space bands 11 between the jaws 21 and 23, and finally he lifts the tool 6 to withdraw the space bands 11 from the space band box 8.

From the above description, it is evident that a plurality of space bands 11 may be quickly and easily placed in a space band box or removed therefrom.

From what has been said, it will be understood that the tool described is capable of modifications as to details of construction and arrangement within the scope of the invention herein disclosed and claimed.

25 What I claim is:

A tool of the class described formed of a long, thin bar that is flatwise in a vertical plane, one end portion of the bar affording a relatively long handle and the other end portion thereof 30 affording a relatively short space band carrier, the upper edge of which is substantially parallel to the upper edge of the handle but spaced materially below the same, the upper edge of the inner end portion of the handle being inclined to the upper edge of the space band carrier, said space band carrier having on its outer end an upstanding fixed jaw, a long movable jaw for cooperation with the fixed jaw in the form of a narrow channel through which the bar extends 40 endwise with the bottom of the channel at its outer end engaging the lower edge of the bar as a guide, said movable jaw having in its sides longitudinally extended slots, and a pin intermediate secured to the bar with its end portions extending into said slots and holding the movable jaw for tilting movement about the axis of the pin, one of the side members of the movable jaw at its inner end being upwardly extended and bent laterally to afford a thumb-piece.

50 GEORGE L. CURLE.
